Primary Examiner — Sheryl Lane*Assistant Examiner* — Emily Anna Saunders(74) *Attorney, Agent, or Firm* — Millman IP Inc.(57) **CLAIM**

The ornamental design for a toy vehicle, as shown and described.

DESCRIPTION

FIG. 1 is a perspective view from above, to the rear and the right side of the new design for a toy vehicle;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawings, the broken lines are for the purpose of illustrating portions of the article that form no part of the claimed design.
